UNITED STATES PATENT OFFICE.

HARRY H. BURTON, OF NEW BEDFORD, MASSACHUSETTS, ASSIGNOR TO DRAPER CORPORATION, OF HOPEDALE, MASSACHUSETTS, A CORPORATION OF MAINE.

SPOOLER BOBBIN HOLDER.

Application filed September 3, 1926. Serial No. 133,488.

This invention relates to a bobbin holder for spoolers and similar machines where the yarn is wound off from the bobbin or filling carrier on to a spool or suitable yarn receiver.

In the type of machine to which this invention relates, the bobbin lies in a generally horizontal, but slightly inclined position on a suitable rest and the yarn is drawn off 10 from the bobbin under suitable guards resting against the yarn mass and positioning the bobbin on the rest.

The mass of yarn on the bobbin obviously varies from the full quantity at the beginning of the winding operation to nothing when the operation is concluded. The mass of yarn also varies with the size of the bobbin. It is desirable also to have the yarn mass on the bobbin as large as can be advantageously handled on the spooler. It will be seen, therefore, that the tension on the yarn drawn off from the bobbin will vary greatly under these varying conditions. This varying condition is further accentuated by the vibration or jumping of the bobbin during the winding operation.

The object of the present invention is to provide a simple and efficient means for controlling the tension on the yarn as it is 30 unwound from the bobbin.

The object of the invention is further to provide means presenting a yield or give in the rest upon which the bobbin is supported so as to ease the shock when the bobbin 35 jumps or vibrates and thus reduce the strain on the yarn.

The object of the invention is further to provide a simple construction which may readily be applied to existing bobbin holders for securing the desired results.

These and other objects and features of the invention will appear more fully in the accompanying description and drawings and will be particularly pointed out in the claims.

As the invention relates entirely to the means for supporting the bobbin during the spooling or winding operation and as the general construction and operation of the spooler or winding machine are well known and familiar to those skilled in the art, it is only necessary to illustrate and describe that portion of the machine with which the present invention, in a preferred form, is directly concerned.

In the drawings:

Fig. 1 is a side elevation of a bobbin holder of an ordinary type with a preferred form of the present invention embodied therein with the ordinary supporting bar of the spooler frame shown in cross section. 60

Fig. 2 is a front end elevation of the construction shown in Fig. 1.

Fig. 3 is a detail in perspective of a bobbin rest employed in this invention.

The ordinary spooler frame is provided with bars such as 1 extending longitudinally of the frame at each side. On these bars are mounted, extending horizontally and slightly upwardly away from the frame, a series of bobbin holders each supporting a 70 bobbin from which the yarn is drawn, in the spooling operation, to the spools above on the frame. The bobbin holders are all alike so that it is only necessary to illustrate and describe one of them. 75

The ordinary bobbin holder comprises a bracket 2 forked at its lower end to embrace the bar 1 and locked thereto, as by the set screw 3. This bracket carries, secured thereto or integral therewith, a support or pan 4 80 having a concave central section 5 and side flanges 6. The upper surface of this pan inclines upwardly, and upon this surface the bobbin usually rests with the yarn mass in contact with the concave section. 85

From the bracket 2 extends upwardly, and overhanging the pan, an arm 7 in which is pivotally mounted a pair of wire guards 8. These guards swing by gravity against opposite sides of the yarn mass 9 on the bobbin 10 and thus maintain the bobbin in proper position on the pan or support. The yarn as it is drawn off from the bobbin during the winding operation, passes around and beneath one of these guards. 95

It will thus be seen, that no provision is made for varying the surface upon which the bobbin rests or changing the character of that surface, when the pan alone is used, whatever may be the size of the yarn mass, 100 the weight and size of the bobbin and yarn mass, or the character of the yarn.

In the present invention there is provided a plurality of concave yielding rests preferably made of strips of sheet spring metal. A 105 preferred form of one of such rests is shown in Fig. 3. The central portion 11 is concave and on a flatter arc than the concavity of the section 5 of the pan. The ends of the rest are bent as indicated at 12 loosely to 110

engage the flanges 6 of the pan or support.

It will be seen that the width and character and number of these rests may be varied as required by the particular conditions. Two or more of these rests, as required are slipped in place on the pan or support. Two of these rests are shown in Fig. 1.

Thus the weight of the bobbin is taken off from the extended surface of the pan or support and transferred to the surfaces of these rests.

Not only, therefore, is the width and character of the supporting surfaces for the bobbin under control but also the spring or yield in the rests themselves is found to be a highly desirable factor in preventing breakage of yarn due to the vibration or jumping of the bobbin when the mass of yarn is relatively large and heavy. It is found that by the use of these rests, the speed at which the spooler is operated may be substantially increased. It has thus been found possible to increase the speed about 40%. Furthermore, owing to the fact that the breakage of the yarn is very substantially reduced, the labor required in piecing the ends and maintaining the spooler in operation is materially reduced. It is found that one operator can handle three times as many spindles as heretofore.

It will also be seen that the invention, as in the preferred form illustrated, may readily be applied without alteration to existing spooler frames which is of great advantage.

The present invention, therefore, enables the yarn to be wound tightly and in a large mass on the bobbin in the spinning room and the spooler to be run at high speed because of the control of the tension provided by this invention, and all this is done by a simple construction readily applied to existing spooler frames.

Having thus described the invention, what is claimed as new, and desired to be secured by Letters Patent, is:

1. A bobbin-holder for spooler frames comprising a support presenting a plurality of concave yielding rests extending transversely of and longitudinally spaced along the support to hold the bobbin during the spooling operation.

2. A bobbin-holder for spoolers having the construction defined in claim 1 in which the rests are removably mounted on the support whereby any number, size and spacing thereof may be employed to control the tension on the yarn.

3. A bobbin-holder for spooler frames having the construction defined in claim 1 in which each rest is a narrow strip of sheet spring metal.

4. A bobbin-holder for spooler frames having the construction defined in claim 1 in which each rest is a narrow strip of sheet spring metal having hooked ends loosely embracing the side edges of the support.

In testimony whereof, I have signed my name to this specification.

HARRY H. BURTON.
